UNITED STATES PATENT OFFICE.

JOHN R. GAMMETER, OF AKRON, OHIO

DRIVING MECHANISM.

1,076,416.

Specification of Letters Patent. Patented Oct. 21, 1913.

Application filed December 22, 1911. Serial No. 667,265.

To all whom it may concern:

Be it known that I, JOHN R. GAMMETER, a citizen of the United States, residing in the city of Akron, county of Summit, and State 5 of Ohio, have invented certain new and useful Improvements in Driving Mechanism, of which the following is a specification.

In aeroplanes as constructed at the present day, the lifting effect is produced by 10 driving the aeroplane forward, so as to cause the planes, which are tilted at a slight inclination toward the front of the machine, to slide up, so to speak, upon the supporting strata of air. The lifting is thus entirely 15 dependent upon a forward movement of the machine, and if the power urging the machine forward fails, it will fall back to the earth, or, under favorable conditions, may be caused to glide back more or less gently 20 by a skilful operator. For driving the aeroplane forward, one or more propellers have heretofore been used, driven by an engine of the internal combustion type. While engines of this type have been de- 25 veloped to such a point that they are remarkably reliable in operation, it is nevertheless true that with an engine delicately constructed, as an aeroplane motor must be, accidents will sometimes, and frequently do, 30 occur which cause the motor unexpectedly to cease its operation. Such unexpected stoppage of the engine is the most dangerous contingency with which aviators have to contend, and more than any other cause 35 has been the occasion of those accidents which have rendered aviation the most hazardous of all pursuits.

My present invention relates to improved means for driving aeroplanes and the like, 40 whereby a plurality of motors may be used, which under normal conditions unite in driving the propeller or propellers, but so arranged that if either of the motors fails in its operation, the other will continue to 45 drive the aeroplane forward, and thus prevent an accident. The probability of both motors simultaneously ceasing to operate is so remote that the danger of the aviator being left without power is practically eliminated. I accomplish this result by connecting the motors by means of a differential, 50 from the floating or driven member of which I derive the power for rotating the propeller or propellers of the aeroplane. By this means, under normal conditions, the propeller or propellers receive the power of

both motors, being driven at a speed proportional to the mean speed of the motors, the rotation of the propellers being automatically accomplished by either of the motors 60 singly in case the other motor or motors cease to operate.

In the accompanying drawings which form a part of this specification, Figure 1 is an elevation of a pair of motors connected 65 by means of a differential in accordance with my invention, the differential being shown in section, and illustrating one embodiment of my improved power unit. The motors shown in this figure are of the rotary or Gnome type, in which the cylinders and frame of the engine rotate about a fixed crank; Fig. 2 is a section upon line II—II of Fig. 1; Fig. 3 is a section on line III—III of Fig. 1; Fig. 4 is a plan view of a modification of my device showing diagrammatically portions of two multiple-cylinder non-rotary motors of standard type, the differential being shown in section; Fig. 5 is a diagrammatic plan view of an aeroplane 80 provided with one form of my improved power unit, the upper main plane being removed and portions of the lower plane being broken away; Fig. 6 is a vertical longitudinal section through the aeroplane shown 85 in Fig. 5.

Referring in detail to the drawings, and particularly to Figs. 1, 2, 3, 5 and 6, the form of my improved power unit shown in these figures comprises a pair of rotary motors 1 and 2 constructed to rotate in the same direction. The frames of each of these motors has projecting from it a sleeve 3 which terminates in a flange 4. To each of the flanges 4 is secured a plate 5 provided with 90 a central boss 6, in which is secured a stub shaft 7. Mounted upon suitable bushings 8 carried by these stub shafts is the casing 9 of a differential. The ends of the stub shafts 7 project into this casing and each 100 of them has keyed thereto a beveled gear 10. Mounted upon bushings 11 carried by the hubs of these beveled gears 10 is a spider 12 having one or more arms, preferably four, from the ends of which project journals 13, upon which are mounted beveled pinions 14 meshing with the beveled gears 10. The journals 13 terminate in pins 15 which are received within sockets 16 projecting from the inside of the casing 9. 110 The outside of the casing has formed upon it one or more sprockets 17, from which

chains 18 and 19 lead to sprockets on the shafts of the propeller or propellers.

In Figs. 5 and 6, my power unit is shown as mounted upon the frame 20 of an aeroplane, the latter being provided with two propellers 21 and 22 driven in opposite directions, as in the Wright machine. The propellers are mounted upon shafts 23 on the inner ends of which are sprockets, one of which is driven by the open chain 18, while the other is driven by the crossed chain 19.

It is to be understood, of course, that my invention is not limited for use with aeroplanes provided with two propellers, as the differential may obviously be connected in a suitable manner to drive a single propeller in aeroplanes of the type using but one propeller.

It will be understood that in the normal operation of my device both motors are operated in the same direction and at as near a uniform speed as is practicable. For this purpose they may advantageously be arranged with a common control for the carbureter and the ignition systems of each, although this is not necessary. The speed of the differential casing and of the propeller or propellers will be the mean of the speeds of the two motors, in any case. If, however, one of the motors should cease to operate, there would be a tendency for the second motor to drive it backward through the differential. In order to secure the effective operation of one motor without the other, it is therefore necessary to provide means to check this tendency and prevent backward operation of the "dead" motor. I have provided means for this purpose which form an important part of my invention.

As shown in Figs. 1, 2 and 3, each of the motors is provided with a ratchet or clutch device 24 for preventing backward rotation. This clutch device may be of any suitable form, but I prefer to construct the same as follows: To the flange 4 and plate 5 of each motor I secure a ring 25 having a flange 26 engaging the side of the plate 5, a flange 27 seating upon the edges of flange 4 and plate 5 and an outwardly extending flange 28. Mounted upon the outer surface of the flange 27 and firmly secured against rotation thereon is a ring 29, preferably of hardened steel, this ring being provided with inclined seats 30 and with abutments 31 having vertical stop faces 32. Retained between the seats 30 and the stop faces 32 are hardened steel clutch rollers (or balls) 33. The clutch rollers are prevented from lateral displacement in one direction by the flange 28 and in the other direction by a cover plate 34 secured to the edge of the flange 27. The flanges 27 and 28 and the cover plate 34 thus form an annular channel

in which are mounted the clutch rollers. Mounted between the side walls of this channel and practically closing the same, is an annular member 35, preferably faced on its inside with a ring 36 of hardened steel, which engages the clutch rollers 33. Means are provided for preventing the rotation of the annular member 35 and its facing ring 36, these means preferably consisting of an arm 37 projecting from the annular member and engaged upon each side by stops carried by a fixed part of the aeroplane frame. These stops are preferably of the form shown in Figs. 2 and 3 and comprise supports 38 carrying plungers 39 which engage the sides of the arm 37. The stems 40 of the plungers 39 slide through holes formed in the supports 38, the plungers being held in operative position by means of stiff springs 41. In operation it will be seen that when the motors are both revolving forward, as indicated by the arrows in Figs. 1, 2 and 3, the clutch rollers 33 will be carried around by the abutments 31 and will slide or roll freely within the ring 36. Upon one of the motors stopping, however, the other continuing in operation, there will be a tendency for the motor which has stopped to be driven backward through the differential. The first backward movement will, however, cause the rollers 33 to ride up the inclined seats 30 on the ring 29, causing the rollers to jam against the inner surface of the ring 36. The ring 36 being held against rotation, however, the backward movement of the motor will be immediately checked. The use of the spring stops for the annular member 35 permits the latter to yield slightly and prevents injury from the shock which would otherwise occur upon the sudden stoppage of the motor.

In order to facilitate the simultaneous starting of the two motors, I preferably provide means for locking the differential so that the two motors will be obliged to rotate in unison during the cranking. A suitable device for accomplishing this purpose is illustrated in Fig. 1. As shown in that figure, I provide one or more of the pinions 14 with lugs 42 which are adapted to be engaged by locking pins 43 passing through openings formed in the side of the differential casing 9. The pins 43 are carried on a spider 44, the hub of which, 45, is slidably mounted upon a sleeve 46 forming a part of the differential casing 9. The movement of the spider 44 and pins 43 is limited by means of a pin 47 fixed in the side of the differential casing, passing through a hole in one of the arms of the spider and provided with an enlarged head 48. The movement of the spider is controlled by means of a knurled nut 49 screwed upon the threaded end of the sleeve 46 and provided with a neck 50 carry-

ing a flange 51 received within a groove in the hub of the spider.

In the operation of this device, when the engines are to be cranked up, the nut 49 is 5 operated to move the spider toward the side of the differential casing, thus bringing the pins 43 into engagement with the lugs 42. This device is shown with the parts in this position in Fig. 4. The motors are thus 10 locked together through the differential and are obliged to rotate in unison. The motors are then cranked, preferably by rotating one of the propellers 21 or 22 by hand. After the motors are started, the spider 45 and the 15 pins 43 may be withdrawn into the position shown in Fig. 1 by exerting a pressure of the hand upon the nut 49, which is rotating rapidly, thus checking its rotation sufficiently to cause it to screw along the 20 threaded portion of the sleeve 46 and thus withdraw the spider. The two motors will now be connected only through the differential, the casing of which will be driven at a speed equal to the mean speed of the 25 motors. If either of the motors ceases to operate, it will be prevented from backward revolution by means of its clutch device and the differential casing will be driven at one-half the speed of the motor remaining in 30 operation, the propeller or propellers being driven at a correspondingly reduced speed. The motors, however, are each of a power adequate to drive the propellers at a sufficient speed to keep the aeroplane in the air 35 and under control, and the aviator may either continue on his journey with one motor or seek a suitable spot at which to land and repair his second motor.

In Fig. 4 I have shown a modification 40 of my invention in which I use a pair of motors 52 of any usual form of non-rotary type, one of the stationary cylinders of each of the motors being shown at 53, the remaining cylinders of the motors being 45 broken away. The main shafts 54 of the motors each carry one of the beveled gears 10 of the differential, which is shown in this figure as of the same construction as that shown in Fig. 1 and previously described in detail. Each of the main shafts 54 also carries a clutch disk 55, the periphery of which is provided with inclined seats and abutments of the form shown in Figs. 2 and 3. Surrounding these disks are the 55 annular channeled members 56 which carry the clutch rollers 33, holding the latter in engagement with the seats and abutments formed on the disks 55. The annular channels 56 correspond in operation with the 60 annular members 35 previously described, and are provided with suitable means, preferably such as illustrated in Figs. 2 and 3, for preventing their rotation. The operation of the form of my device shown in

Fig. 4 is exactly the same as that of the 65 form of my invention shown in the other figures of the drawings and already fully described.

It is to be understood that I have shown and described in detail, and by way of illustration of the principle of my invention, merely a preferred embodiment thereof. I do not intend to limit myself to this specific embodiment, but desire to cover broadly the principle of my invention, consisting in the 70 use of a plurality of motors connected by means of a differential or its equivalent, so that the motors may operate together to drive the aeroplane, or so that either motor alone will act to drive the aeroplane in case the other 75 motor ceases to operate. Moreover, while my invention is particularly applicable to the propulsion of aeroplanes, I do not desire to limit myself to its use solely for that purpose, as it may be found advantageous for 80 many other purposes; for example, for the driving of dirigible balloons, automobiles, motor boats, and, in general, wherever else uninterrupted application of power is 85 desirable.

Having thus described my invention, I claim:

1. In a power unit for aeroplanes and the like, a pair of motors adapted to rotate in the same direction, a differential gearing 95 and its casing, means to cause said motors to rotate in unison comprising a lug on a gear of said differential gearing, and a pin passing through an aperture in the casing of said differential gearing and adapted to be 100 moved into and out of engagement with said lug, and means for preventing the backward rotation of either of said motors comprising 105 roller clutches interposed between each of said motors and said differential casing.

2. In a power unit for aeroplanes and the like, a pair of motors adapted to rotate in the same direction, a beveled gear driven by each of said motors, a differential casing, a beveled pinion carried by said casing and 110 meshing with said beveled gears, power-transmission means carried by said casing, means for preventing the backward rotation of either of said motors, and means for locking said beveled pinion against rotation to 115 cause said motors to rotate in unison, said means including a screw-threaded member normally adapted to rotate with said casing, a second screw-threaded member, the threads 120 on which engage those of the first-named member, and clutching means operated by movement of said second member.

3. In a power unit for aeroplanes and the like, a pair of motors adapted to rotate in the same direction, a beveled gear driven by 125 each of said motors, a differential casing, a beveled pinion carried by said casing and meshing with said beveled gears, power-

- transmission means carried by said casing, means for preventing the backward rotation of either of said motors, and means to lock said beveled pinion against rotation to cause 5 said motors to rotate in unison, said means comprising a lug on the pinion, a pin passing through an aperture in the side of the differential casing and adapted to be moved into and out of engagement with said lug, 10 said pin being carried by a member slidably mounted upon a sleeve projecting from the side of said differential casing, and a nut screwing on a portion of said sleeve and engaging said member.
- 15 4. In a power unit for aeroplanes and the like, a pair of motors adapted to rotate in the same direction, a gear driven by each of said motors, a differential casing, means carried by said casing meshing with said gears, 20 power-transmission means carried by said casing, means for preventing the backward rotation of either of said motors, said means comprising a disk rotatable with each of said

motors, a stationary member mounted adjacent to said disks, clutch means mounted between said rotatable disk and stationary member and acting to prevent the rotation of said disk except in one direction, the means for retaining said stationary member stationary comprising an arm projecting 30 from said member and spring-pressed abutments engaging the sides of said arm.

5. In a power unit for aeroplanes and the like, a pair of motors adapted to rotate in the same direction, differential gearing connecting said motors, and means to cause said motors to rotate in unison comprising a lug 35 on a gear of said differential gearing, and a pin passing through an aperture in the casing of said differential and adapted to be moved into and out of engagement with said lug.

JOHN R. GAMMETER.
